EMBROIDERY STITCHING SEWING MACHINE

Arnaldo Vigorelli, Pavia, Italy

Application November 23, 1953, Serial No. 393,760

Claims priority, application Italy January 28, 1953

4 Claims. (Cl. 112—158)

This invention relates to an ornamental or embroidery stitching sewing machine of the so-called "zigzag type" designed to produce at high speed predetermined ornamental designs of embroidery stitching upon various kinds of fabrics and/or other material of similar character. More particularly, it relates to a new and useful control device in sewing machines of the type referred to above, having a vertically reciprocating and laterally movable needle or needles, a drive shaft for reciprocating said needle or needles and cam means in mechanical driving relationship with said shaft for laterally moving said needle or needles according to a predetermined cycle of stitching operation.

Several types of zigzag sewing machines for embroidery stitching have been heretofore proposed and currently produced. In the sewing machines of most advanced design the control devices for laterally moving the needle are provided with interchangeable cam means whereby many varieties of designed stitches may be made in differing predetermined patterns, means being also provided for easy substitution of the one cam member actually in operation within the device with another differently shaped cam member, for having another different ornamental embroidery or fancy stitches produced, when desired.

The sewing machines of the above known type are subject to the common objection that it is necessary to take the cam member out of the machine and substituting thereof another cam member in its operative position in the machine. Said operations require a certain mechanical skill and may be performed as the machine is at standstill only. Further, a number of differing cam members must be at disposal for having a like number of different ornamental or embroidery patterns.

Having said objection in mind, I provide a novel and useful sewing machine, according to this invention, which includes, in combination, a vertically reciprocated and laterally movable needle or needle assembly, a drive shaft for reciprocating said needle or assembly, and a control device for controlling the lateral movement of said needle or assembly and provided with a plurality of cam members and with transmission means for operatively relating said needle or assembly, alternately and at will, to each one of said cam members, whereby a plurality of embroidery patterns may be obtained.

Another object of this invention is to provide, in a sewing machine of the character referred to above and including a plurality of cam members, control means designed for having the said transmission means, at will, set in operative relationship either with whatever single cam member comprised in said plurality or with two of

2

said cam members, whereby a number of predetermined embroidery patterns may be obtained by the co-operation of one or more pairs of cam members in addition to the number of different predetermined embroidery patterns which may be obtained by the operation of any single cam members.

A further object of this invention is to provide a new and useful arrangement for a plurality of cam members whereby any or substantially any single cam member comprised in said plurality may be readily substituted and/or set in other operative position in respect of other cam members comprised in the same plurality, whereby by using the same cam members a further large plurality of embroidery patterns may be produced at will by interchanging the same members within the device, in relation of the pair or pairs of co-operating cam members.

A still further object of this invention is to provide, in a sewing machine of the type referred to above and provided with a plurality of cam members, a new and useful hand-control device whereby the transmission means provided for laterally moving the needle or the needle assembly may be operatively connected to any cam member or pair of co-operating cam members by simple action exerted on an external hand-lever or button, or the like, regardless of whether the machine is at standstill or in operation.

A still other object of this invention is a general improvement of sewing machines of the zigzag type and in particular for current sewing and for embroidery stitching, in relation both to construction and to operation thereof.

These and other important objects that will be made apparent as this description proceeds are accomplished by the novel construction, combination and arrangement of parts hereinafter described and illustrated in the accompanying drawings, constituting an essential component of this disclosure, and in which:

Figure 1 is a diagrammatical vertical sectional view of a sewing machine comprising the combination of operative parts according to this invention;

Figure 2 illustrates a control device embodying the features of this invention in a preferred form of embodiment thereof, illustrated partly in section and partly in plan view of the assembly comprising the operative parts, supported in a horizontally sectioned casing;

Figure 3 is partly a side view and partly a cross sectional view, taken on line 3—3 of Fig. 2, of the detail including the plurality of cam members;

Figure 4 is an elevation view of the casing of the machine, in the portion thereof comprising the hand-control and regulation means;

Figure 5 illustrates a detail of a regulating device, shown in a sectional view taken on line 5—5 of Fig. 2;

Figure 6 illustrates the detail of the transmission means comprised in the control device, partly in section and partly in elevation, as it appears looking in the direction indicated by 6—6 in Fig. 2;

Figure 7 illustrates the detail of another regulating device, shown partly in elevation and partly in sectional view taken on line 7—7 of Fig. 2;

Figure 8 illustrates diagrammatically the combination of transmission members of Fig. 1, to demonstrate the action thereof on regulating the device of Fig. 6, and

Figures 9a to 9o inclusive illustrate in a rather diagram-

matical, enlarged plan view examples of various embroidery designs in zigzag stitching which may be produced by the use of an improved machine embodying the invention, without changing of cam members, and by the operation of the various single cam members included in the said plurality and by the co-operation of some pairs of same cam members in relative adjacent relationship.

Like reference numerals refer to like or equivalent parts, members and features throughout the several figures of the accompanying drawings.

In general, a sewing machine improved according to this invention and comprising a vertically reciprocating and laterally movable needle, a drive shaft for reciprocating said needle and means for laterally moving same, includes a shaft means rotatably supported in the machine's casing or structure, gear means or other equivalent transmission device for rotatively connecting said drive shaft to said shaft means, a plurality of disk-shaped cam members interchangeably supported on and rotatively connected to said shaft means, in relative co-axial and side-by-side relationship, a cam following finger member designed to co-operate with said cam members and movably supported on a rocking arm or equivalent device spanning the whole plurality of said cam members, transmission means for operatively connecting said rocking arm to said laterally movable needle for having the latter moved according to the motion of said rocking arm, and hand-controlled means for moving said cam following finger along said spanning rocking arm for putting said finger in following relationship with whatever cam member is comprised in said plurality.

In a preferred form of embodiment of this invention, the said hand-controlled means are designed to put, at will, the said cam following finger either in a position such to co-operate with the cam shaped periphery of a single cam member and in a position intermediate to a pair of adjacent cam members, such to have said finger in following relationship with both peripheries of said cam members, and whereby to have the said rocking arm moving according to the salients of both said cam members.

In rather more detail, as shown in Fig. 1, all parts and members of the devices produced according to the invention are enclosed in and protected by the upper portion 10 of the machine's casing. Said casing will not be described in detail and it will be shown in the accompanying drawings in part only, the construction of said casing and likewise of all other devices not forming essential parts of this invention being matter comprised within the range of knowledge of those skilled in the art and thereby indicated by the expression "according to current art" or by an equivalent thereof as this description proceeds. According to current art, the machine comprises a needle-bearing member 11 slidably supported by a swinging lever 12 for having said needle axially reciprocated for its conventional sewing action, and said swinging lever 12 is pivotally supported at 13 to the frame structure 14 of the machine, for allowing the lateral motion of said needle in view of the production of zigzag sewing. An intermediate portion of the drive shaft for reciprocating said needle is indicated by reference numeral 15, the said drive shaft 15 operating said needle by means of a conventional crank means (not shown) or other reciprocating device produced according to current art.

In Figs. 1, 2, 3, 6 and 8 reference numeral 16 generally indicates the plurality of cam members, or "cam unit," the construction of which will be described in detail below, and which substantially comprises a number of disk-shaped cams, say six cams, of like basic diameter and thickness, in co-axial and side-by-side relationship and connected one to other as to form a unit rotatably supported about a shaft 17 made integral with said frame structure 14 of the machine. The said cam unit 16 is operatively connected to and driven by said drive shaft 15 by means of helical gears 18 and 19, for example, made

integral with said cam unit 16 and with said drive shaft 15, respectively. Reference numeral 20 indicates a cam following finger, designed to follow the notched periphery of the cam members, and supported at one end of a rocking bell crank lever means 21 swingably supported at 23 about a shaft made integral with same structure 14 and having its axis parallel to the axis of said cam unit 16. At its other end 22, the said rocking bell crank lever means 21 is pivotally connected to the upper end of a short link member 24 the lower end of which is connected at 25 to one end of a long link member 26. The other end of same long link member 26 is pivotally connected at 27 to a two-armed swingable lever 28 pivotally supported at 29 about a shaft made integral with said frame structure 14. By a pivotal and slidable connection at 30, said swingable arm 28 co-operates with said swinging lever 12, through an extension 31 thereof.

Provided that the pivot constituting the said pivotal connection at 25 is confined to move along a predetermined path (by means of guiding and regulating devices described below), as said cam unit is rotatively driven by drive shaft 15 in cyclical relationship with the reciprocating motion of needle, and provided that the said cam following finger 20 is positioned in following relationship with the notched periphery of at least one cam track of unit 16, the said rocking oscillating arm 21 is subjected to a rocking motion according to the sequence of salients and hollows of said periphery and through the described linkage members 24, 26 and 28 the said oscillatable needle controlling member 12 is subjected to lateral movement according to a predetermined cycle of operation related to the cam track pattern of said periphery, whereby a given embroidery pattern may be produced by the zigzag controlled action of the sewing needle.

The above said primary object of this invention is attained, according to the invention, by the combination of a cam unit of the character described, comprising a plurality of cam means, and of means for displacing the cam following means 20 on the end of said rocking lever 21.

In the preferred form of embodiment shown in Figs. 2, 3 and 4, the cam unit 16 includes six cam members 16a, 16c, 16e, 16g, 16h and 16j. Cam member 16a is formed by an out-turned flange extension 40 of an outer tubular member 41, supported by, rotatably connected to and axially removable from an inner tubular member 42, which is made integral with said helical gear 18 (Fig. 3). Said inner tubular member 42 is rotatably supported about said shaft 17 and axially held by abutments on a step 43 of same shaft 17 and on a heading screw 44, for example. When turning, said tubular member 41 (forming cam 16a) is held in its axial operative relationship with inner tubular member 42 by abutment on an out-turned flange forming extension 45 of the latter member and by a screw-cap 46 in threaded connection with one end of said inner member 42, arranged outside casing 10 of the machine and designed to be screwed on and off by hand.

Said tubular member 41 acts as supporting means for other cam means 16c, 16e, 16g, 16h and 16j which are constructed in form of disks 47. Said cam disks are held about said tubular member 41 in co-axial and abutting relationship one to other and to the cam forming flange 40 by a large disk member 48, threaded on the end of member 41 opposite to flange 40. Said disk member 48 covers when correctly screwed on said member 41 an opening 49 and that, by unscrewing the said disk member large enough to admit removal of the described cam unit 16, when required.

In view of the common requirement of producing "regular" zigzag sewing, the periphery of cam member 16a is preferably machined to form a cam track having a pattern of evenly spaced and dimensioned salient-and-hollow array for having the lateral zig-zag motion of the needle imparted as the reciprocal motion of same is. On the contrary, the other cam tracks are designed to impart to the oscillatable needle control member 12, various

cycles of movements, differing in amplitude and/or sequency, for having the desired various embroidery designs or patterns produced.

From what has been set forth above and in particular by a consideration of Fig. 3 of the accompanying drawings, it will be readily understood by those skilled in the art that by un-screwing the said cap 46 the whole cam unit may be easily removed from the machine through opening 49 and that, by unscrewing the said disk member 48 from the end of tubular member 41 the disk-shaped cam members 47 may be removed from said tubular member whereby said cam unit is disassembled. One or more disk-shaped cam members 47 may be substituted for setting the machine to produce one or more other embroidery patterns, and/or the position of one or more disk-shaped cam members 47 may be varied, as to have one or more said members set in adjacent relationship with disk-shaped members other than the ones in adjacent relationship prior to said disassembling.

The construction of the said rocking arm 21 for having the cam following finger 20 displaceable thereon may be carried out in various embodiments which those skilled in the art may readily devise. In the preferred form of embodiment shown in Figs. 2 and 3 the said rocking arm 21 is provided with a lateral extension 50 spanning over the whole axial length of the plurality of cam members and constituting a supporting means. Into said extension 50 a rod 51 is slidably supported and axially movable, and the said rod 51 has the said cam following finger 20 radially projecting therefrom, through a groove 52 (Fig. 3). Members 51 and 20 constitute cam follower means.

The said rod 51 is provided with an end 53 positioned outside the extension 50 of rocking arm 21 and pivotally and slidably connected at 54, by means of a conventional pin-and-groove connection as shown in Fig. 2, for example, to one end of a two-armed lever 55 pivoting about pin 56 screwed in the machine's frame structure 14. The other end of same two-armed lever 55 is provided with a pin 57 slidably engaging with an helical groove 58 of a shaft 59 (Fig. 2) rotatably supported by said frame structure 14 extending out-side the front flank 10' of the casing 10 of the sewing machine, and made integral with a hand button 60 whereby said shaft 59 may be easily rotated by hand. The rotatable unit comprising said button 60 is preferably provided with a suitable conventional means for having the same maintained in whatever angular position of a plurality of angular positions at any one of which, by means of the described co-operating members, the said cam following fingers rests on the notched periphery of one cam member or at an intermediate position between two adjacent cam members, for co-operating with the peripheries of both said members. Said means may comprise, for example, a ball 61 movably supported inside a hole drilled in said button 60 and pressed by a helical spring 62 on a base plate 64 made integral with casing 10 and provided with a set of correspondingly angularly spaced hollows in which said ball may rest. The said button 60 is further provided with an indicating circular scale 63 whereby the angular position of said button, and subsequently the operative position of cam following finger 20, may be observed and determined by the operator.

Still further, the described combination of parts and members, which co-operate for forming the "control device" of the machine in view of the production of differing embroidery patterns, comprises means for facilitating the displacement of cam following finger 20 along extension of rocking arm 21, and more particularly for having said finger raised from the co-operating periphery or peripheries of cam members in view of its lateral movement in respect thereof. For example, as shown in Fig. 1 and partially in Fig. 4, said means comprises a push-button 65 normally kept in up-raised position by spring means, by a coil spring 66 for example, and so positioned that as it is pressed the rocking arm 21 is compelled to

rock counter-clockwise (Fig. 1) raising said finger and having the same free to be laterally displaced.

As it will be apparent to those skilled in the art, by the provision of a control device as above described and shown in the accompanying drawings, or of an equivalent thereof, a zigzag sewing machine improved according to this invention may be set for production of varied ornamental or embroidery patterns by a simple turning of said button 60 or by handling an equivalent device, an hand lever connected to said two-armed lever 55, for example. Further, it will be apparent that said device may allow the production of differing embroidery patterns the number of which exceeds the number of the single cam members comprised in said cam unit, owing to the fact that the said cam following finger may co-operate with two co-operating adjacent cam members besides that with any single cam member. Still further, it will be apparent that by having at disposal a comparatively small number of different disk-shaped cam members, a very large number of predetermined embroidery patterns may be produced, besides the ones attained by the individual cam members and by the co-operation of adjacent cam members; because by removing and disassembling the said unit, as above described, said cam members may be reset about the said tubular member 41 in many differing relative adjacent relationships.

One example of the advantages given by the provision of an improved control device produced and operated according to this invention will be now made evident by referring to Figs. 9a to 9o, and by supposing that in the cam unit 16 the notched peripheries of cams 16a, 16c, 16e, 16g, 16h and 16j are provided with salients and hollows designed, by applying current knowledge in the art, to produce an embroidery pattern as shown in Fig. 9a and respectively in Figs. 9c, 9e, 9g, 9h and 9j, the whole series of said Figs. 9a to 9j inclusive representing the order and the sequency of the patterns, any one of which may be produced at will by simply setting the machine 20 with the use of hand button 60 only, either when the machine is at standstill or in operation.

More particularly, by turning hand button 60 as the cam following finger 20 will rest on the periphery of cam member 16a only, a regular or "normal" zigzag pattern will be produced. Preferably, the said graduation 63 of button 60 will be provided with an indicating sign "N" positioned to refer to a reference arrow 67 (Fig. 4) at said operative condition of parts. The same graduation will be provided with signs "1", "2 . . . 5" positioned to have the operative positioning of said finger with the first, the second and respectively the fifth cam arranged in the cam unit 16 beyond "basic" cam 16a, and with intermediate signs between said numeral signs.

In Fig. 9a said regular or "normal" zigzag pattern is diagrammatically illustrated in different width in portions A, B and C of same figure, the variation of width being attained, from a maximum to zero, by acting on a suitable width regulating device of the type currently produced and applied to sewing machines of zigzag type. A preferred form of embodiment of said device will be described in detail below, as forming additive matter of this application. Likewise, all other embroidery patterns that the machine may produce may have their width varied as desired but for sake of simplicity in Figs. 9b to 9o they are illustrated in their maximum width.

By turning the said button 60 from position marked "N" to a position intermediate between positions marked "N" and "1" the said cam following finger will be displaced in position intermediate between cam members 16a and 16c, and an embroidery pattern as shown in Fig. 9b may be produced, said pattern being a combination of the patterns produced by cam members 16a and 16c, separately operating, and shown in Figs. 9a and 9c, respectively, owing to the fact that said finger 20 is compelled to follow the salient portions of both said cam

members. Then by turning same button 60 to the position marked "1" the pattern shown in Fig. 9c is produced by the operation of single cam member 16c, and so on. The patterns shown in Figs. 9e, 9g, 9h and 9j are produced by the operation of single cam member 16e and respectively 16g, 16h and 16j, and the embroidery patterns shown in Figs. 9d, 9f and 9i are produced by the co-operation of pairs of adjacent cams 16c and 16e, and respectively 16e and 16g, and 16h and 16j. The pattern that might be produced by the co-operation of adjacent cam members 16g and 16h is not shown as of not practical use being substantially alike the pattern produced by cam member 16h alone.

From the above it will be readily apparent that by the use of a sewing machine of the type described and improved by the application of a control device according to this invention and comprising a cam unit involving one "basic" cam member and five "embroidery" cam members in the co-axial and co-operative relationship set forth, a great number of, say ten, differing embroidery stitching patterns or designs may be produced and that any one of said patterns may be selected by the operator by simple action on the button 60.

Still further, in Figs. 9k to 9o a few examples of further differing embroidery patterns which may be produced by using same machine and same cam members in different arrangement in the cam unit are shown. By setting cam member 16j in a position adjacent to cam member 16a the patterns shown in Fig. 9k is produced, the said pattern being a combination of the regular zig-zag pattern with pattern shown in Fig. 9j; by setting cam member 16c adjacent to cam member 16g or to cam member 16h the pattern shown in Fig. 9-l and respectively shown in Fig. 9m may be produced, and by setting cam member 16j adjacent to cam member 16e or to cam member 16g the pattern shown in Fig. 9n and respectively in Fig. 9o may be produced. It will be obvious that a plurality of other patterns may be produced by setting the various cam members in further different relative positions in the cam unit. It will be obvious also that by providing for the operator other cam members besides the ones normally mounted in one cam unit still other embroidery patterns both in separately operating and in co-operation with other ones may be easily produced.

A sewing machine produced according to this invention is provided with means for guiding the point of pivotal connection at 25 between the short link member 24 and the long link member 26 along a fixed path. Said guiding means and the function thereof will be explained with reference to Figs. 2, and 4 to 8 inclusive, either in respect to the construction and the operation of a preferred form of embodiment thereof. According to said form of embodiment, the said pivotal connection at 25 is constituted by a pivot made integral with a square-faced block 70 slidable along a diametral groove 71 of a disk-shaped member 72 made integral with a short shaft 73 traversing the front side of the machine's casing and having an end portion 74 projecting outside the front surface 10' thereof (Figs. 2 and 5). At its end portion 74 the said shaft 73 is a firmly connected to a handle 75 and it is rotatably supported in the hub forming portion 76 of a two-armed, L-shaped lever 77, the construction of which will be made apparent below.

By turning the said handle 75 the direction of said diametral groove 71 the path along which the said pivotal connection at 25 is confined may be varied at will, within practical limits. Suitable indicating means, an indicating arrow 78 for example, may be provided for making apparent the position of said groove, and more particularly said indicating arrow will cooperate with a graduation impressed on a front plate 79 (Figs. 4 and 7) and comprising numerals indicative of the width of the zigzag sewing produced. Further, the said handle 75, i.e. the guiding means controlled by said handle, are kept in

the desired position by suitable braking devices, by a friction plate 80 rotatively connected to same handle 75 and pressed against the said front plate 79 by a coil spring 81, for example, as shown in Fig. 5. The described assembly of means comprising members 70, 72 and 75 and the parts connected thereto, and which will be designated "width controlling device," is preferably further improved by the application of means for limiting the amplitude of the possible regulation between a maximum value (depending on the construction of the machine) and a "zero" value, said limiting means being constituted by a flat lever 82 rotatively connected to said handle 75 (made integral with said friction plate 80, for example, and constituted as a radial extension thereof) and co-operating with displaceable stop members, as stop buttons 83 and 84 for example, arranged along a circular groove 85 of said front plate 79, displaceable therealong and which may be made firm at any point thereon, as desired (Figs. 4, 5 and 7).

The operation of the described width controlling device above described will be explained below with reference to the diagrammatical Fig. 8 of the accompanying drawings. Provided that by the construction and the operation of the above described assembly of members and parts the direction of path along which the said pivotal connection at 25 is confined, the variation of said direction, between direction D'-D' and direction D"-D" affects the amplitude of swinging motion of the two-armed lever 28 (i.e. of the lateral motion of the needle) in respect to the amplitude of the rocking motion of said rocking arm 21, the latter amplitude depending on the deepness of the notching of operating cam member or of co-operating cam members. As the said groove 71 is directed to confine the said pivotal connection at 25 along a path in direction D'-D', which is perpendicular to the alignment of said pivotal connection at 25 to the pivotal connection at 27 between long link 26 and two-armed lever 28, any motion of the actual small extension of said pivotal connection at 25 along said direction D'-D' does not cause a motion in said pivotal connection at 27, but only a slight rotative movement of said long link 26 about said point 27, which acts as center point. On the other hand, supposing that the position of the described guiding means of said pivotal connection at 25 is such as to confine the movements thereof along a path in direction D"-D", for example, the said movements cause the motion of pivotal connection at 27 as a function of the component along line 25-27 of the amplitude of the movement along D"-D". It will be readily understood by those skilled in the art that by angularly modifying the direction of the path along which the said pivotal connection at 25 moves, a component along line 25-27 of the desired amplitude may be obtained whereby the width of the plain zigzag or of the embroidery stitching that is being produced may be varied at will down to zero width. The various described parts and members are designed and arranged for having the said indicating arrow 78 pointed at indicating sign "0" as the direction of groove 71 is perpendicular to line 25-27.

In the preferred form of embodiment of the invention shown in Figs. 2, 4, 5, 6 and 7 the sewing machine improved according to this invention is further provided with a "lateral displacement device" for the purpose of having at will the middle sewing alignment displaced to the left or to the right with respect to the regular sewing alignment, according to the most modern practice of embroidery or ornamental sewing and for meeting certain sewing requirements known by those skilled in the art. In general, said lateral displacement device includes means for displacing the position of member 72 acting as guiding means for the said pivotal connection at 25. Referring now to said figures, the said member 72 and the shaft 73 made integral therewith are rotatably supported

in one end portion 76 of a two-armed L-shaped lever 77 pivotally supported about a pin 86 fixedly connected to the machine frame, and provided with another fork-shaped end portion 87. Between the prongs of said fork-shaped portion 87 a pin 88 is slidably arranged, the said pin being made integral and in eccentric relationship with a shaft 89 rotatably supported in the casing 10 (Fig. 2).

The said shaft 89 is firmly connected at its portion outer of said casing to a second handle 90.

As consequence of the above described arrangement and combination of parts, as the said handle 90 is turned the said eccentric pin 88 causes the two-armed lever 77 to swing about its pivot 86 and the axis about which the said guiding member 72 is rotatably supported to be displaced, thus the whole assembly of the width controlling device is correspondingly displaced for having the whole assembly comprising the described members co-operating for imparting the lateral movements to the needle in operation in a different spatial arrangement and relationship. Owing to the fact that, for the operation of the described lateral displacing device the position of handle 75 controlling the width controlling device is modified in respect to the front flank of casing 10, the described indicating signs pointed by arrow 78 are not impressed on the surface 10' of said casing but on the said front plate 79 which is not firmly connected to said casing but slideable on the front surface 10' thereof, and which is traversed by said shaft 73, whereby said front plate 79 is correspondingly displaced. Further, for the purpose of keeping the said pointer 78 in correct pointing relationship with the sign which indicates the width of the zigzag sewing actually produced, the said front plate 79 is traversed by the said shaft 89 of second handle 90, the said shaft 89 being provided with an eccentric portion 91 (Figs. 2 and 7) at its front plate traversing position, the said eccentric portion 91 being designed to cause the left side of said plate to move as the right portion thereof (traversed by shaft 73) is displaced.

The lateral displacement device is preferably also provided with means for having its parts kept firmly at its "centre," "left" and "right" operative positions, the said means comprising, for example, a ball 92 kept by a coil spring 93 in abutting relationship with the rear surface of a flange forming extension 94 of said shaft 89 provided with hollows in which said ball may partially rest.

While I have illustrated and described but one form of embodiment of this invention, I do not intend to be limited to the detail shown, since various modifications and structural changes may be made thereto without departing in any case from the spirit of this invention.

Without further analysis, the foregoing will so fully reveal the gist of my invention and the mode by which the same may be carried on and operated that by applying current knowledge one can readily adapt it for various applications without omitting features that, from the standpoint of prior art, fairly constitute essential characteristics of this invention. For example, in a sewing machine of the type described and provided with a plurality of cam members, the advantageous provision of separately constructed and detachably supported and arranged cam members in the cam unit might in certain cases be omitted, and a one-piece cam unit comprising a plurality of co-axial zones of differently shaped and notched peripheries might be also produced in lieu thereof. Further, the auxiliary devices named, for simplicity sake, width controlled device and lateral displacement device might be omitted in view of a simpler and/or cheaper production, or in view of certain uses of the machine in which the regulation of width and/or lateral displacement of sewing alignment are not required. Still further, the whole assembly comprising the plurality of cam members, in the various forms of possible embodiment thereof and named in its unity "embroidery patterns control device," may be constructed as a unit separate from

the machine and designed to be applied to previously produced standard zigzag types of sewing machines, as an embroidery stitching attachment therefor.

Such adaptations, omissions and variations should and are therefore intended to be comprehended within the meaning and range of equivalents of the appended claims.

What I claim as new and desire to have protected by Letters Patent is:

1. In combination with a sewing machine of the zig-zag type described, having a vertically reciprocating and laterally movable needle and a drive shaft for reciprocating said needle; a multiple embroidery stitch forming control device comprising cam means for laterally moving said needle according to a predetermined cycle of operation, said control device comprising a cam unit rotatably supported in the machine, gear means rotatively connecting said cam unit to said drive shaft, a plurality of cam forming portions having differently notched peripheries of like basic diameter and in co-axial and adjacent relative arrangement, one cam following finger designed to co-operate with said notched peripheries, arm means rockably supported in the machine and having an end extension spanning over the said cam unit in direction parallel to the axis thereof, means for supporting said cam following finger on said arm means and for having same displaceable along the said spanning extension thereof, hand operated means externally arranged to the machine and mechanically connected to said displaceable cam following finger for having same displaced along said spanning extension, and a mechanical transmission for operatively connecting said rockably supported arm means to said laterally movable needle; said cam unit comprising an inner tubular member rotatably supported in the machine, an outer tubular member removably supported on said inner tubular member, and a plurality of disk-shaped cam members each one of which is provided with one notched periphery and is removably supported about said outer tubular member in the said relative arrangement; and gear means rotatively connecting said drive shaft to said inner tubular member for driving the same and said tubular and disk-shaped members.
2. In combination with a sewing machine of the zig-zag type having a reciprocating and laterally movable needle and a drive shaft for reciprocating said needle; a multiple embroidery stitch forming control device for laterally moving said needle according to a predetermined cycle of operation, said control device including a cam unit, said cam unit comprising an inner tubular member rotatably supported in the machine, an outer tubular member removably supported on said inner tubular member, and a plurality of disc-shaped cam members each of which is provided with a notched periphery and is removably supported on said outer tubular member, said cam members and tubular members being in coaxial and adjacent relative arrangement, and said notched peripheries having like basic diameters, a cam follower finger having an engaging portion cooperating with said notched peripheries, arm means rockably supported in the machine, means for supporting said cam follower finger on said arm, means for movement between a plurality of positions in which said engaging portion thereof cooperates with said peripheries of said disc-shaped cam members; operating means externally arranged to the machine and mechanically connected to said cam follower finger for moving the same between said positions; a mechanical transmission for operatively connecting said rockably supported arm means to said laterally movable needle; and gear means for connecting said drive shaft to said inner tubular member for driving the same.
3. An arrangement as set forth in claim 2 wherein said mechanical transmission comprises two link members, a pivot means connecting said two link members, one of said link members being driven by said rockably supported arm means, and the other link member laterally

11

driving said laterally movable needle, means for guiding said pivot means along a predetermined path, and manually operable means for modifying the direction of said predetermined path for having the amplitude of the driving action of said other link member varied with respect to the amplitude of the driven motion of said one link member.

4. An arrangement as set forth in claim 3 wherein said pivot means includes a slide member; wherein said means for guiding said pivot means includes a turnable member formed with an elongated recess slidably guiding said slide member along said predetermined path, and wherein said manually operable means are means for turning said turnable member.
